Primary Examiner — Brett Miller*Assistant Examiner* — Rani J Abdallah(74) *Attorney, Agent, or Firm* — Quarles & Brady LLP**CLAIM**

The ornamental design for a bottle, as shown and described.

DESCRIPTION

FIG. 1 is a top, front, left perspective view of a bottle of the new design;

FIG. 2 is a front elevational view of FIG. 1 which is identical to a rear elevational view thereof;

FIG. 3 is a left side elevational view of FIG. 1 which is identical to a right side elevational view thereof;

FIG. 4 is a top plan view of FIG. 1; and,

FIG. 5 is a bottom plan view of FIG. 1.

The broken lines illustrate portions of the bottle that form no part of the claimed design.

1 Claim, 4 Drawing Sheets---
